UNITED STATES PATENT OFFICE.

NORRIS ELMORE CLARK, OF PLAINVILLE, CONNECTICUT, ASSIGNEE TO ROBERT S.
ALLYN, TRUSTEE, OF NEW YORK, N. Y.

EXPANDED-METAL MACHINE.

1,321,090.

Specification of Letters Patent. Patented Nov. 11, 1919.

Application filed March 7, 1917. Serial No. 153,152.

To all whom it may concern:

Be it known that I, NORRIS ELMORE CLARK, a citizen of the United States of America, residing at Plainville, Hartford county, Connecticut, have invented a new and useful Expanded-Metal Machine, of which the following is a specification.

My invention relates to a machine for expanding slotted stock and is intended particularly for the expansion of a fabric such as shown in Sheet 1 of my Patent No. 930,350. The machine is claimed broadly in my Patent No. 1,146,553.

Figure 1 is a side view of a machine embodying the improvements of my invention.

Fig. 2 is a partial section on the plane of the line 2—2 of Fig. 1.

Fig. 3 is a partial section on the plane of the line 3—3 of Fig. 1.

20 The stock to be treated is first slotted for instance by mechanism as shown in my Patent No. 1,146,554 so that it is made up of longitudinal unslotted strips connected by sections slotted along diagonal lines.

25 10 is a table with suitable side gages for receiving slotted stock. 11 and 12 are upper and lower rolls respectively for engaging and feeding the stock. It is only necessary for these rolls to engage the unslotted strips. 30 13—13 represent lower rolls spaced apart from each other and arranged on a shaft below the rolls 12. Rolls 12 and 13 are preferably connected by bands or chains 14 for engaging unslotted strips and assisting in the feeding of the stock. The marginal band may be wider than the others, as indicated in Fig. 3, to give a more positive tractive force.

Above each roll 13 is a ring or annular 40 member 15 which presses against the roll 13 and also toward the roll 12 for guiding and holding the marginal and interior unslotted strips.

Between each two adjacent lower rolls 13 I arrange an upper roll 16 which projects downwardly so as to carry the center of the slotted section relatively away from the unslotted strips constituting the margins of the slotted section. The band or chain 17 passes 50 around each roll 16 and the roll 11 so as to assist in directing and moving the center of the slotted section. This band also passes around part of the upper face of roll 12. A guide such as 18 may be provided to direct

the marginal and interior unslotted strips 55 from between the rolls 11 and 12 to the ring 15. Guides such as 19 and 20 may also be provided for directing the mesh work away from the opening mechanism.

The shaft of the rolls 11 may be supported 60 in boxes such as 21 which are vertically adjustable. Similarly the shaft for the rolls 13 may be supported in vertically adjustable boxes 22. Rollers 23 and 24 engage each ring 15. Each pair of rollers 23 and 24 is 65 carried by a yoke 25 on the shaft 26 which has a vertically adjustable box 27 at each end so that the pressure of the rollers 23 and 24 may be varied. The tension of the bands 14 and 17 may be adjusted by means of rollers such as 28 and 29.

The slotted stock is fed to this opening mechanism with the strands of each slotted section inclined forwardly and toward the center of the slotted section. By reason of 75 the fact that the marginal and interior unslotted strips pass around the curved surfaces of the rings 15 at the same time that the centers of the slotted sections pass around the correspondingly curved surfaces 80 of the rolls 16, the slotted sections are opened into mesh work without buckling the strands and with but very little strain upon the metal or the machine. The rolls and bands may be driven in any suitable manner. 85

I claim:

1. In an expanded metal machine, two pairs of upper and lower rotary disks for feeding parallel unslotted strips of a partially slotted sheet in one plane, two more 90 pairs of upper and lower rotary members in line respectively with the said rotary disks for feeding out said strips in a plane spaced apart from the first plane, and a rotary member between said pairs of rotary members 95 for carrying the center of a slotted section out of the plane of said unslotted strips as the stock moves forward.

2. In an expanded metal machine, two pairs of upper and lower rotary disks for feeding parallel unslotted strips of a partially slotted sheet in one plane, two more 100 pairs of upper and lower rotary members in line respectively with the said rotary disks for feeding out said strips in a plane spaced apart from the first plane, a member between said pairs of rotary members for carrying the center of a slotted section out of

- the plane of said unslotted strips as the stock moves forward and traveling bands around corresponding lower rotary members.
3. In an expanded metal machine, two spaced apart rotary annular members, rotary disks engaging said annular members, a shaft passing through said annular members, an intermediate disk on said shaft having one edge extending between said rotary disks and means for feeding unslotted strips of a partially slotted sheet around an arc of said annular members while the center of the slotted section moves around a corresponding arc of said intermediate disk.
4. In an expanded metal machine, a plurality of annular members, two sets of rolls coacting therewith for feeding unslotted strips of partially slotted stock, rotating members eccentric to said annular members and projecting into spaces between the rolls of one of said sets of rolls and around said intermediate rotating members.
5. In an expanded metal machine, a plurality of annular members, two sets of rolls coacting therewith for feeding unslotted strips of partially slotted stock, rotating members eccentric to said annular members and projecting into spaces between the rolls of one of said sets of rolls and around said intermediate rotating members.
6. In an expanded metal machine, a plurality of annular members, two sets of rolls coacting therewith for feeding unslotted strips of partially slotted stock, rotating members eccentric to said annular members and projecting into spaces between the rolls of one of said sets of rolls and means for adjusting said annular members toward one of said sets of rolls.
7. In an expanded metal machine, means for engaging a plurality of longitudinally extending unslotted strips of a partially slotted sheet and feeding the same in one plane and deflecting them all gradually into a second plane and means for engaging the central portions of the slotted sections between the strips and carrying the same gradually into a third plane parallel to but spaced apart from the second plane to expand the meshwork, said engaging and expanding means including continuous moving bands.
8. In an expanded metal machine, a plurality of annular members, two sets of rolls coacting therewith for feeding unslotted strips of partially slotted stock, rotating members eccentric to said annular members and projecting into spaces between the rolls of one of said sets of rolls and a band extending around corresponding rolls of the two sets of rolls and extending around a part of one face of the corresponding annular members.
9. In an expanded metal machine, a plurality of annular members, two sets of rolls coacting therewith for feeding unslotted strips of partially slotted stock, rotating members eccentric to said annular members and projecting into spaces between the rolls of one of said sets of rolls, a band extending around corresponding rolls of the two sets of rolls and extending around a part of one face of the corresponding annular members, and a directing band extending around one of said sets of rolls and around said intermediate rotating members.
10. In an expanded metal machine, a plurality of annular members, two sets of rolls coacting therewith for feeding unslotted strips of partially slotted stock, rotating members eccentric to said annular members and projecting into spaces between the rolls of one of said sets of rolls, a band extending around corresponding rolls of the two sets of rolls and extending around a part of one face of the corresponding annular members, a directing band extending around one of said sets of rolls and around said intermediate members and means for adjusting the tension of one of said sets of bands.
11. In an expanded metal machine, a plurality of annular members, two sets of rolls coacting therewith for feeding unslotted strips of partially slotted stock, rotating members eccentric to said annular members and projecting into spaces between the rolls of one of said sets of rolls, a band extending around corresponding rolls of the two sets of rolls and extending around a part of one face of the corresponding annular members, a directing band extending around one of said sets of rolls and around said intermediate members and means for adjusting the tension of one of said sets of bands.
12. In an expanded metal machine, a plurality of annular members, two sets of rolls coacting therewith for feeding unslotted strips of partially slotted stock, rotating members eccentric to said annular members and projecting into spaces between the rolls of one of said sets of rolls, directing bands connecting corresponding rolls of the two sets of rolls and means for adjusting the tension of said bands.
13. An expanded metal machine, two series of rotary feed disks, the disks of each series being spaced apart from each other to receive the unslotted strips of a partially slotted sheet and draw the same into the machine, two more series of rotary feed members arranged to engage the same unslotted strips of the stock and feed the same away in another plane from the entrance plane and a series of intermediate rotary members with their bearing faces arranged eccentric for drawing the centers of the slotted sections into a plane parallel to the

delivery plane of the unslotted strips and thereby producing relative longitudinal movement and opening the mesh.

14. An expanded metal machine, a receiving table for the stock having its supporting face in one plane, a series of delivery rails having their bearing faces in another plane spaced apart therefrom, two series of disks for feeding the partially slotted stock from said receiving table, two series of rotating members for feeding the stock onto said delivery rails and intermediate rotating members for engaging the centers of slotted sections and carrying them into a plane parallel to the bearing faces of the delivery rails but spaced apart therefrom to thereby produce relative longitudinal movement and open the mesh.

15. In an expanded metal machine, a series of annular feed rings, a shaft extending transversely of the machine, means for adjusting said shaft relative to said annular feed rings and two series of rollers carried by said shaft and engaging said feed rings and two series of rotating members coacting with said feed rings opposite said rollers.

16. In an expanded metal machine, two

series of rotating members for engaging the unslotted strips of the partially slotted sheet and feeding the sheet in two more sets of 30 rotating members for engaging the same unslotted strips to feed the sheet out in a different plane, a series of intermediate rotating members for engaging the centers of the slotted sections and carrying them into an other plane parallel to, but spaced apart from the delivery plane of the unslotted strips and guide bands coacting with said intermediate rotating members.

17. In an expanded metal machine, means 40 for engaging a plurality of longitudinally extending unslotted strips of a partially slotted sheet and feeding the same in one plane and deflecting them all gradually into a second plane, said engaging, feeding and deflecting 45 means including continuous moving bands, and means for engaging the central portions of the slotted sections between the strips and carrying the same gradually into a third plane parallel to but spaced apart 50 from the second plane to expand the mesh-work.

NORRIS ELMORE CLARK.
